UNITED STATES PATENT OFFICE.

EUGENE FRANK VARACHE, JR., OF LIBERTY, NEW MEXICO.

ADJUSTABLE AND FOLDABLE SAWHORSE.

1,150,794.

Specification of Letters Patent. Patented Aug. 17, 1915.

Application filed March 18, 1915. Serial No. 15,243.

To all whom it may concern:

Be it known that I, EUGENE FRANK VARACHE, Jr., a citizen of the United States, and a resident of Liberty, San Juan county, 5 and State of New Mexico, have invented a new and Improved Adjustable and Foldable Sawhorse, of which the following is a full, clear, and exact description.

This invention relates to a saw horse and 10 has to deal more particularly with a saw horse having adjustable and foldable legs, whereby the range of usefulness of the device is greatly increased.

The invention has for its general objects 15 to improve and simplify the construction and operation of devices of the character referred to so as to be reliable and efficient in use, comparatively simple and inexpensive to manufacture and of durable and substantial design.

A more specific object of the invention is 20 the provision of a saw horse having longitudinally extensible legs whereby the saw horse can be used on sloping surfaces and 25 staircases, as well as on the level.

Another object of the invention is the provision of a novel, simple, durable hinge connector for uniting the legs with the bar or body of the saw horse, whereby the legs can 30 be folded into a compact space when the saw horse is not in use.

With such objects in view, and others which will appear as the description proceeds, the invention comprises various novel 35 features of construction and arrangement of parts which will be set forth with particularity in the following description and claims appended hereto.

In the accompanying drawing which illustrates 40 one embodiment of the invention, and wherein similar characters of reference indicate corresponding parts in all the views, Figure 1 is a side view of a saw horse set up for use, the legs having intermediate 45 portions broken away; Fig. 2 is an enlarged vertical sectional view of the hinge joint that connects the legs with the bar of the saw horse; Fig. 3 is an enlarged sectional view on the line 3—3, Fig. 1; Fig. 4 is a 50 horizontal section on the line 4—4, Fig. 3; and Fig. 5 is an upper sectional view of the foot portion of a leg.

Referring to the drawing, A designates 55 the body or bar of the saw horse, and B and B' are the legs at each end which are connected with the bar A by hinges C.

Each leg is composed of telescoping pipe sections 1, 2 and 3, as clearly shown in Figs. 1 and 5, whereby the legs can be lengthened or shortened, according to the shape of the 60 surface on which the saw horse is to stand. A set screw 4 clamps the inner and intermediate sections 1 and 2 together, and a set screw 5 clamps the outer and intermediate sections together. By loosening these set 65 screws the sections of the leg can be slid inwardly or outwardly to shorten or lengthen the leg. When the legs are to rest on surfaces where slipping of the saw horse must be avoided, sharpened spurs 6 are set into 70 the lower ends of the inner sections 1 and are clamped by set screws 7. If the saw horse is to rest on a polished floor or any other surface that must not be marred, the spurs are pushed back into the legs far 75 enough so that their points will not protrude, and when in this position the spurs are clamped by the set screws 7. When the spurs are to be set in protruding position the screws 7 are loosened, and a spring 8 disposed behind each spur will force the same 80 outwardly, and when in the desired position the screws 7 are re-tightened.

Each hinge C comprises a fixed section c and a movable section c'. The section c 85 comprises a plate fastened to the under side of the bar or body A and it is provided with spaced depending lugs 10. The section c' of the hinge consists of a plate 11 having a pair of members 12 extending in spaced parallel relation to each other and at right-angles to the plate 11, and the extremities of these members are respectively connected by pivots 13 with the lugs 10 of the fixed section c. The movable section of the hinge 95 is thus an L-shaped structure, and the legs B and B' are independently pivoted to the plate 11 by bolts 14, whereby the legs can be moved toward or from each other, as shown by full and dotted lines in Fig. 3. 100

When the horse is set up for use the legs B and B' are spread apart or flare downwardly and they are held from spreading too far by stops formed by flanges 15 on the lateral edges of the plate 11. These 105 flanges are curved and shaped at their extremities 16 to coöperate with the plate 11 for forming clips, whereby the legs cannot accidentally move inwardly from the position shown in Figs. 3 and 4. A cross-bar 110 or link 17 is connected with the inner ends of the pivot bolts 14 so as to steady the

same and stiffen the structure. The stop flanges 15 are connected by brace bars 18 with the ears or lugs 12 so as to render the structure more rigid.

- 5 When the saw horse is in use the members or ears 12 bear against the fixed sections *c* of the hinge, as shown in Fig. 2, and a suitable catch device is used to prevent the legs at both ends of the saw horse from folding 10 inwardly, such catch device consisting of a spring catch 19 pivotally mounted at 20 on the section *c'* of the hinge, and having a shouldered portion 21 that extends into an opening 22 in the fixed section *c* of the hinge 15 and there interlocks with the latter. The catch device is automatically locked as the legs are swung from the folded or dotted-line position shown in Fig. 2 to the open or full-line position, but when the legs are to 20 be folded the catch device is manually released so that the legs can be folded to a position parallel with the bar A. When in folded position a hook 23 pivoted on the cross bar 17 of each pair of legs is engaged 25 with an eye or equivalent device 24 on the under side of the saw horse bar, as shown by dotted lines in Fig. 2.

From the foregoing description taken in connection with the accompanying drawing, 30 the advantages of the construction and method of operation will be readily understood by those skilled in the art to which the invention appertains, and while I have described the principle of operation, together with the device which I now consider 35 to be the best embodiment thereof, I desire to have it understood that the device shown is merely illustrative and that such changes may be made when desired as fall within 40 the scope of the appended claims.

Having thus described my invention, I claim as new and desire to secure by Letters Patent:

1. A horse comprising a body bar, a plate 45 fastened to the underside of the bar and having depending lugs, an L-shaped device having one member pivotally connected with the lugs, and said member being adapted to bear against the plate, legs pivotally mounted on the other member of the device, said 50 plate having an opening, and a spring-

pressed catch mounted on the second-mentioned member of the device and projecting upwardly above the first member to extend into the opening of the plate and interlock 55 with the latter for maintaining the legs in operative position.

2. A horse comprising a body bar, a plate thereon having lugs, an L-shaped device having one member pivotally connected with 60 the lugs, and said member being adapted to bear against the plate, legs pivotally mounted on the other member of the device, said plate having an opening, a spring-pressed catch mounted on the second-mentioned 65 member of the device to extend into the opening of the plate and interlock with the latter for maintaining the legs in operative position, said legs and catch mounted on the same side of the member to which they are 70 attached, and combined stops and yielding clasps on the leg-carrying member for grasping the legs and limiting the spreading movement of the latter.

3. A horse comprising a body bar, hinges 75 each including a fixed section on the under side of the body bar and a movable section in the form of a plate having members adapted to bear against the fixed section and pivotally connected to the latter, means for 80 locking the movable sections stationary with respect to the fixed sections, supporting legs pivotally mounted on the movable sections, and resilient flanges forming combined clasps and stops on the movable sections for 85 holding the legs in operative position.

4. A horse comprising a body bar, depending plates thereon, legs pivoted on the plates, and stops on the edges of the plates for 90 limiting the spreading movement of the legs, said stops being formed by flanges having yielding extremities coöperating with the plates for forming clasps for engaging the legs and preventing accidental inward movement of the latter.

In testimony whereof I have signed my name to this specification in the presence of two subscribing witnesses.

EUGENE FRANK VARACHE, JR.
